UNITED STATES PATENT OFFICE.

RAFAEL DIAZ BUITRAGO, OF NEW YORK, N. Y.

SUCTION DUSTER.

1,423,993.

Specification of Letters Patent.

Patented July 25, 1922.

Application filed March 9, 1921. Serial No. 450,910.

To all whom it may concern:

Be it known that I, RAFAEL DIAZ BUITRAGO, a citizen of the United States, residing at New York city, in the county of

5 New York and State of New York, have invented certain new and useful Improvements in Suction Dusters, of which the following is a specification, reference being had therein to the accompanying drawing.

10 This invention is a novel suction duster, especially such a device as is adapted to cleaning furniture, walls, mouldings, and the like, as distinguished from floors, carpets, etc., and operating by manual power.

15 It is an object of the present invention to provide such a device which can be grasped and manipulated by a single hand, leaving the other hand free, or cooperating with the other hand in which an auxiliary brush

20 or dust collector can be employed. Another object is to provide a mechanism of the kind referred to which will remove dust, lint, and other light dirt, with efficiency yet with little effort on the part of the user.

25 A further object is to afford a device which is self-contained and compact, therefore cleanly and always in readiness for use. The herein described embodiment is of extreme lightness in weight, thereby obviating the tiring of the user, yet is free from need of adjustment or detachment, and is strong and durable in operation.

To the attainment of the above recited objects and advantages the present invention consists in the novel suction duster or cleaner herein illustrated or described and the novel features of arrangement, combination, structure and detail disclosed.

Figure 1 is a perspective view of the 40 mode of fitting, handling and operating the device of the present invention.

Figure 2 is a side elevation of the mechanism detached from the dust bag.

Figure 3 is a central section of the same 45 taken on line 3—3 of Fig. 4.

Figure 4 is a plan view of the casing cover removed.

The illustrated suction duster is shown as comprising a box or casing 7 of cylindrical 50 form and of small size, readily grasped in the hand. At one side is shown an inlet passage 8 at the extremity of which is the inlet mouth or nozzle 9 adapted to be applied flatwise to the surface to be cleaned, it being sometimes sufficient to bring this 55 aperture into close proximity to the object

being cleaned. The suction mouth may be supplemented by a brush 10 extending clear across the width of the mouth.

The inlet passage conducts the stream 60 of air to the central interior portion of the casing. At a circumferential point, preferably opposite to the inlet, is shown an exit passage 11 to which is connected by screw threads a coupling ring 12 permanently united with a flexible tube or conveyor 13, which opens out into a dust bag or cloth receptacle 14 for the dirt. It is an important part of the present invention that it is operable by one hand, and for this 65 purpose I have devised the following arrangement for maintaining the dust bag away from the surface being cleaned. The spring clip 15, which closes the rear end of the receptacle or bag, is provided with a 70 hook or link 16 attachable to a circlet 17 which is placed over the arm of the user near the elbow.

The cylindrical casing 7 is provided with a removable cover 18 held in place by 80 screws 19. To assist the firm grasping of the apparatus, the cover is provided with a beaded edge 18^a under which the fingers rest, and the body of the casing is provided with a lug or projection 20 for the forefinger, and an opposite lug or projection 21 for the little finger. The thumb rests upon a movable grip piece 22, which may be knurled. The casing may be formed with a circumferential slot at 23, and the motion 90 of the thumb piece when in operation may be in accordance with the double arrow 24, Fig. 4.

Within the casing is shown a horizontal partition or wall 25 separating the interior 95 into a lower or pneumatic chamber 26, and an upper or gear chamber 27. The partition rests upon a shoulder 28 on the inside of the casing and is firmly held from rotation by three small projections 29 engaging nicks in the partition plate. The plate is held downward in place by means of an interior flange or sleeve 30 formed integral with the cover 18.

What may be termed the main shaft 33 of 105 the apparatus is centrally located and at its lower end carries a fan and fly-wheel, later described. The shaft turns through a ball bearing, the upper race 34 of which is carried upon the shaft, while the lower race 110 35 is secured to the under side of the partition 25.

To give greater stability and uniformity of operation, a fly-wheel 36 is mounted on the main shaft, being threaded thereon and held in position by a lock nut 37. For drawing in the air through the inlet passage and forcing it out tangentially, I prefer a centrifugal fan which may possess a series of six blades 38 mounted on and extending downwardly from the web of the fly-wheel. Preferably the lower edges of the blades are united by means of an annular disk 39 brazed to the blades.

For driving the fly-wheel and fan at high speed from the thumb piece 22, the following multiplying gearing may be used. The shank 42 of the thumb piece plays in the slot 23. The shank is secured rigidly with a member 43, the body of which is ring shape but which is preferably closed at the top so that it is cap shape and constitutes the outer member of the clutch or one-way drive device. The clutch member or cap 43 is provided with a hub 44 mounted on a short vertical shaft 45, which takes its bearing in the partition 25 and an overhanging bracket 46. The clutch consists of the ring member 43 cooperating with a series of clutch rollers 47 and an interior clutch member 48 having a wedge surface 49 for each roller. This device does the work of a pawl and ratchet, affording drive in one direction only as the thumb piece is reciprocated, but the device is silent in action and more efficient than ordinary pawl and ratchet. The interior clutch member 48 is connected with a gear 50. By this arrangement whenever the thumb piece is thrown to the left, in Fig. 4, this gives the gear 50 a clockwise rotation, but when the thumb piece is returned this causes no operation.

The driving gear 50 engages with a pinion 51 mounted on the short shaft 52, which takes its bearing in the partition 25 and an overlying bracket or plate 53. Fast on the shaft 52 is also a gear 54 which engages a pinion 55 which is fast on the main shaft 33. This multiplying gearing gives considerable speed of rotation to the fly-wheel and suction fan. It is easily operated by the reciprocating movement of the thumb, and delivers a sufficiently powerful current of air to afford the effects already recited.

I have thus described what may be termed a one-hand suction cleaner consisting of a casing small enough to be grasped within the hand and operated by the muscles of the grasping hand, with proper inlet and outlet, and exterior dirt bag. In the pre-

ferred form, the receptacle is suspended from the wearer's person, possibly from the shoulder or neck but preferably from the forearm or elbow. The means for producing the air flow is operable by the muscles, for example, by a gripping or squeezing action, but preferably the casing is rigid and the air flow produced by a mechanism worked through a reciprocating finger piece or lever, as described. These various features and the details already described are considered to be of novelty and importance in attaining the results hereinbefore recited.

It will thus be seen that a suction duster or cleaner has been described embodying the principles and attaining the advantages of the present invention, and other advantages will be understood to those conversant with the art. Since many matters of combination, arrangement and detail may be variously modified without departing from the underlying principles, it is not intended to limit the invention to such features except in so far as set forth in the appended claims.

What is claimed is:

1. A manually held and operated suction duster comprising a two chambered casing adapted to be grasped by the hand, the suction chamber containing a suction fan, a shaft carrying the fan and extending into the other chamber, multiplying gears in the second chamber adapted to rotate said shaft, a fly wheel on said shaft, an operating lever extending exterior to the casing and adapted to be reciprocated by the muscles of the hand which grasps the casing, and a device by which the operating lever effects rotation of the multiplying gears, and the shaft flywheel, and suction fan.

2. A manually held and operated suction duster comprising a casing of such small size as to be grasped and held in one hand, an operating lever mounted inside the casing and extending through an opening thereof into a position to be contacted and moved back and forth by a finger of the hand which grasps the casing, a suction fan and flywheel within the casing, and multiplying mechanism whereby the operation of said lever effects rapid rotation of said suction fan and flywheel, said casing having a suction opening to be applied to the object to be cleaned, and an outlet for the air and dust.

In testimony whereof, I have affixed my signature hereto.

RAFAEL DIAZ BUITRAGO.
